UNITED STATES PATENT OFFICE.

LOUIS C. TINSLEY, OF NEW YORK, N. Y.

MOLD FOR TYPOGRAPHICAL SLUGS.

Application filed May 16, 1921. Serial No. 470,126.

To all whom it may concern:

Be it known that I, LOUIS C. TINSLEY, a citizen of the United States, and a resident of the city of New York, borough of the Bronx, in the county of Bronx and State of New York, have invented a new and Improved Mold for Typographical Slugs, of which the following is a full, clear, and exact description.

10 This invention relates to improvements in molds for typographical slugs, an object of the invention being to provide a slug comprising a plurality of sections fragilely connected, said fragile portions adapted to be broken away to receive the rules when the slugs are set up in the galley.

15 A further object is to provide a slug of the character stated which can be cast in any ordinary typographical machine employing the ordinary matrices, hence, adding little, if any, to the cost of production and a very slight alteration in the mold structure.

20 A further object is to provide a slug which is especially adapted for use in connection with the setting of tabulated matter.

25 With these and other objects in view the invention consists in certain novel features of construction, and combinations and arrangements of parts, as will be more fully hereinafter described and pointed out in the claims.

In the accompanying drawings—

30 Figure 1 is a view in elevation illustrating a mold in which my improved slug may be cast.

35 Figure 2 is a view in section on the line 2—2 of Figure 1.

40 Figure 3 illustrates in perspective sections of the mold cap, or rather the bottom portion of the mold cap, showing how such sections are constructed and assembled.

45 Figure 4 is a perspective view of my improved slug.

50 Figures 5 and 6 illustrate a modified form of mold cap section.

55 Figure 7 is a perspective view of a modified form of slug made when the cap section shown in Figures 5 and 6 are employed.

50 Figure 8 is a sectional plan view illustrating my improved slug ejector.

55 Figure 9 is a perspective view illustrating the manner of breaking the fragile sections of the slugs when the latter are in position in the galley.

My improved slug 1 indicated in perspec-

tive in Figure 4, comprises a series of sections 2, which are connected at the mold face and at one side of the mold face with integral fragile portions 3. These fragile portions contain as little metal as is necessary to hold the slug in proper formation during handling and assembling, and it is desirable that there be as little metal in the fragile portions as possible so that they may be easily broken out or severed from the sections of the mold after the latter are assembled in the galley 4, as indicated most clearly in Figure 9. This form of slug is especially adapted for tabulated matter.

70 Heretofore, slugs have been cast with recesses in their type faces for the reception of rules, and slugs have been cut for the reception of rules, but in the former case a particular form of matrices is necessary entailing considerable additional expense, and in the latter case not only is there a slow and expensive process, but poor results are frequently obtained.

75 It is my purpose with my improved slug 80 to cast the slug in the machine ready for assembling having its sections of the proper length in accordance with the tabulated matter and having fragile connections between the sections of a proper width, so that when 85 said fragile sections are broken away, there will be just the proper space to receive the rule.

80 It is, of course, obvious that the invention is not limited to the particular manner of 90 breaking the fragile sections, but I have shown in Figure 9 a tool 5 having a blade 6 which can be drawn between the slug sections and sever or break away the fragile portions for the reception of the rule 7.

95 My invention, therefore, resides particularly in the broad idea of forming a cast metal slug composed of sections spaced apart, but connected by fragile integral portions, the sections being of the proper length 100 for the columns of the tabulated work, and containing on their faces type formed by the ordinary matrices of a typographical machine.

105 In forming this slug it is obvious that the exact construction of the mold may be varied within wide limitations, but in order that some means might be illustrated which will show that the invention is a practical one and permit those skilled in the art to form 110 such a slug, I have illustrated one form of mold mechanisms which will carry out the

invention and which of itself is a new invention in its details, wherein it differs from the ordinary mold structure of typographical machine in common use.

5 It is, of course, apparent that it is my invention to provide elements which may be used in the standard typographical machines, so that but slight expense is entailed in the installation of my invention.

10 8 represents the ordinary mold disk, 9 the mold or mold base, 10 the mold cap and 11 the end spaces. The mold cap 10 is provided at its inner face with separable and removable sections 12. These sections 12 have overlapping or rabbeted joints 13 secured together by screws 14, the latter also projecting into blocks 15 which constitute cores of the mold. These blocks 15 are the desired size and shape to form the recesses or spaces between the slug sections, and it is, 15 of course, to be understood that it will be necessary to provide different lengths of cap sections 12 in accordance with the tabulated matter being set.

20 25 In order to properly eject the slug I provide an ejector 16 having a series of ejecting blades 17 of varying widths capable of adjustment by means of screws 18 in any of a plurality of openings 19 in the ejector, so that the necessary adjustment may be had of the blades to properly engage the slug after it is cast.

25 30 The tabulated matter is set up in the ordinary way by the ordinary typographical machines employing the ordinary matrices, one matrix 20 being illustrated in Figure 2, showing the latter in position for casting. The slug space in the mold registers between the matrix 20 and the nozzle 21 of the machine, so that when the metal is forced into the mold, a slug will be cast as is common in the art.

35 40 In Figure 4 the slug is shown having sections spaced apart having flat parallel adjacent walls and this is one form of slug which is probably the best way to cast the same where a pica space is had between the sections. Where it is desired to secure a finer gradation, it is preferable to give at least 45 one end of each mold section a step formation, as shown at 22, in Figure 7. This is 50 accomplished by simply changing the shape of the core block 23 as shown in Figure 6,

so that the space may be reduced between the sections to the thickness desired.

55 Various slight changes might be made in the general form and arrangement of the parts described without departing from the invention, and hence I do not limit myself to the precise details set forth, but consider myself at liberty to make such changes and alterations as fairly fall within the spirit and scope of the appended claims.

60 65 I claim:

1. The combination with a mold for typographical machines, of a mold cap comprising a plurality of sections adapted to be secured together in alignment, means for securing said sections together, and core blocks secured to said mold cap by the securing means of the sections thereof.

70 75 2. The combination with a mold for typographical machines, of a mold cap comprising sections of varying lengths secured in alignment, and core blocks at the juncture of the cap sections.

80 85 3. The combination with a mold for typographical machines, of a cap comprising a series of sections in varying lengths secured in alignment, core blocks carried by the sections, a plunger, and a plurality of plunger blades adjustably connected to the plunger and adapted to engage the slug at opposite sides of the core blocks to eject the slug.

90 95 4. A mold for typographical machines, comprising a mold body, end spaces and a cap having a plurality of sections secured together, core blocks secured to the mold cap at the juncture of the sections, said core blocks adapted to form recesses in the slug whereby the latter is formed into a plurality of sections fragilely connected, and a plunger having a plurality of plunger blades adjustably connected thereto and adapted to engage the slug at opposite sides of the core blocks.

100 5. A typographical mold for forming recesses in a typographical slug whereby the latter is formed into a plurality of fragilely connected sections, said mold comprising a mold body, a sectional cap therefor, means for securing the sections of said sectional cap together, and core blocks secured to the cap by said securing means.

LOUIS C. TINSLEY.
